M. WALTER.
TARGET.
APPLICATION FILED NOV. 27, 1918.

Patented May 28, 1918.

Inventor

Mathew Walter

By Watson E. Coleman

Attorney

UNITED STATES PATENT OFFICE.

MATHEW WALTER, OF EASTON, PENNSYLVANIA.

TARGET.

1,267,722.

Specification of Letters Patent. Patented May 28, 1918.

Application filed November 27, 1916. Serial No. 133,785.

To all whom it may concern:

Be it known that I, MATHEW WALTER, a citizen of the United States, residing at Easton, in the county of Northampton and 5 State of Pennsylvania, have invented certain new and useful Improvements in Targets, of which the following is a specification, reference being had to the accompanying drawings.

10 This invention relates to certain improvements in targets and it is an object of the invention to provide a novel and improved device of this general character which serves to afford amusement and to prove marks- 15manship.

It is also an object of the invention to provide a device of this general character wherein a movable target plate is employed and which has a chance device positioned 20 rearwardly thereof and which chance device is provided with a plurality of indications or valuations and wherein a single indication or valuation is exposed upon a target plate being moved under the influence 25 of the force of the projectile striking said plate.

It is also an object of the invention to provide a device of this general character including a member provided with an opening 30 together with a swinging target plate coacting with said opening and normally closing the same together with means for returning said target plate to its normal position after the same has been caused to 35 assume an open position under the influence of the force of a projectile or from any other cause.

The invention consists in the details of construction and in the combination and 40 arrangement of the several parts of my improved target whereby certain important advantages are attained and the device rendered simpler, less expensive and otherwise more convenient and advantageous for use, 45 as will be hereinafter more fully set forth.

The novel features of my invention will hereinafter be definitely claimed.

In order that my invention may be the better understood, I will now proceed to describe the same with reference to the accompanying drawings, wherein is illustrated a view in perspective with portions broken away of a target constructed in accordance with an embodiment of my invention.

55 As disclosed in the accompanying drawings K denotes a base frame of predeter-

mined dimensions and which is provided with the supporting members 1. At substantially the longitudinal center of the frame K is a transversely disposed beam 2 which is 60 provided with an opening 3. Rotatably supported by the beam 2 and positioned in the opening 3 is the pulley C for a purpose which will be hereinafter more particularly referred to. Carried by the frame K is a 65 housing L including a substantially vertically disposed front plate or wall 4 provided with a series of longitudinally spaced openings 5. Coacting with each of the openings 5 is a target plate A. The lower marginal 70 portion of the plate A is pivotally engaged as at 6 with the lower marginal portion of the coacting opening 5. The plate A snugly fits within the opening 5 and normally closes the same. Engaged with the frame K 75 at a point within the housing immediately adjacent the front plate or wall 4 is a frame B capable of rocking movement in a vertical plane and upon upward movement being imparted to the frame B it will be at once 80 self-evident that a plate A which has been forced into lowered or open position under the influence of a projectile striking said plate is moved back into its normal or closed position.

85 D denotes flexible members suitably secured to the outer or free marginal portion of the frame B and one of said members is directed through an opening 7 produced in the front wall or plate 4 of the housing L, 90 while the second member is disposed through the opening 3 and around the pulley C and extended forwardly of the plate or wall 4 through the depending guide 9 carried by the front wall of plate 4. By imparting pull 95 upon one of the members D it will be at once self-evident that the frame B may be moved upwardly or downwardly as the occasions of practice may require.

100 Positioned within the housing L and rotatably supported by the end walls thereof is a member E herein disclosed as rectangular in cross section and which has each of its faces provided with a series of indications or valuations 10 herein disclosed as 105 numerals, and said indications or valuations 10 are so positioned upon the member E as to permit such valuations or indications carried by a substantially vertical face to be exposed through the openings 5 when the 110 target plates A are in their lowered or open positions.

The member E is adapted to be indiscriminately rotated and for this purpose said member E is provided with a trunnion 11 or the like extending exteriorly of the housing L through an end wall thereof and fixed to said trunnion 11 is a pulley F around which is directed a flexible member J. The strands of the member J are disposed beneath the pulleys 15 mounted in the openings 12 produced in the outstanding plate or cleat 14 carried by an end of the housing L immediately adjacent the pulley F. It will be self-evident that by imparting pull upon the strand of the member J the member E will be rotated and said member E serves as a chance device as the marksman or other participant will be unable to determine the character of the indications or valuations 10 which are substantially in alinement with the openings 5 when the target plates A are in closed position.

It is to be understood that the indications or valuations 10 on the various faces of the member E are not arranged in the same sequence so that the marksman will be unable to determine what indication or valuation will be exposed upon the dropping of a particular target plate A.

From the foregoing description, it is thought to be obvious that a target constructed in accordance with my invention is particularly well adapted for use by reason of the convenience and facility with which it may be assembled and operated and it will also be obvious that my invention is susceptible of some change and modification without departing from the principles and

spirit thereof and for this reason I do not wish to be understood as limiting myself to the precise arrangement and formation of the several parts herein shown in carrying out my invention in practice except as hereinafter claimed.

I claim:

1. A device of the character described comprising a substantially vertical wall provided with a series of substantially horizontally alined openings, a movable target plate normally closing each of said openings and adapted to be moved into open position under the influence of the force of a projectile, a rotatable member positioned rearwardly of the wall and angular in cross section and having each of its faces provided with a series of value indications adapted to be exposed through the openings in the wall when the target plates are in open position, and means for rotating said rotatable member.

2. A device of the character described comprising a substantially vertical wall provided with an opening, a movable target plate normally closing said opening and adapted to be moved into open position under the influence of the force of a projectile, a rotatable member positioned rearwardly of the wall and angular in cross section and having each of its faces provided with a value indication, one of said indications being adapted to be exposed through the opening in the wall when the target plate is in open position, and means for rotating said rotatable member.

MATHEW WALTER.
